UNITED STATES PATENT OFFICE

163,157

TELEVISION CABINET

Samuel E. Adler, Chicago, Ill., assignor to Admiral Corporation, Chicago, Ill., a corporation of Delaware

Application November 28, 1950, Serial No. 13,167

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Television Cabinet, of which the following is a specification, reference being had to the accompanying drawing, forming part thereof.

Fig. 1 is a front elevational view of a television cabinet showing my new design, the doors of which are closed;

Fig. 2 is an elevational view of the right side of the cabinet; and

Fig. 3 is a sectional view taken on line 3—3 of Fig. 1.

The left side of the cabinet resembles the right side and the back is plain.

I claim:

The ornamental design for a television cabinet, as shown and described.

SAMUEL E. ADLER.
